US0D1072223S

(12) **United States Design Patent** (10) **Patent No.:** **US D1,072,223 S**
(45) **Date of Patent:** **** Apr. 22, 2025**

(54) **AROMA DIFFUSER**

(71) Applicant: **Xiangyang Xu**, Hubei (CN)

(72) Inventor: **Xiangyang Xu**, Hubei (CN)

(**) Term: **15 Years**

(21) Appl. No.: **29/903,311**

(22) Filed: **Sep. 22, 2023**

(30) **Foreign Application Priority Data**

May 29, 2023 (EM) 015022904-0001

(51) **LOC (15) Cl.** **23-04**

(52) **U.S. Cl.**

USPC **D23/366**

(57) **CLAIM**

The ornamental design for an aroma diffuser as shown and described.

DESCRIPTION

FIG. 1 is a perspective view of an aroma diffuser showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear, bottom perspective view thereof.

The broken lines in the drawings depict portions of the aroma diffuser that form no part of the claimed design.

1 Claim, 8 Drawing Sheets
